STUB AXLE MINE CAR

Warren V. Johnson and Robert C. Kepner,
Bloomsburg, Pa., assignors to American Car
and Foundry Company, New York, N. Y., a
corporation of New Jersey

Application March 10, 1936, Serial No. 68,000

8 Claims. (Cl. 105—364)

This invention deals with mine cars in general and in particular with mine cars of the stub-axle type for rotary dumping.

It is an object of this invention to provide a mine or similar car having a one piece combined wheel hood, sill and wall connecting member.

Another object of the invention is the provision of a rotary dump mine car having a plate girder side wall with angular chords.

10 A further object of the invention is the provision of a stub-axle car having the girder side wall and outer axle bearing member connected by a strong box-section.

15 A still further object of the invention is the provision of a stub-axle mine car having the inner bearing members connected by a tubular bracing member.

20 These and other objects of the invention will be apparent to one skilled in the art from a study of the following description and accompanying drawings, in which

Figure 1 is a side view of substantially one-half of the car, parts being broken away to more fully disclose the wheel hood;

25 Fig. 2 is a side view of the other half of the car with the bumper being shown in section;

Fig. 3 is an inverted plan view of the car, portions thereof being omitted;

30 Fig. 4 is an end view of slightly more than half of the car, and

Fig. 5 is a sectional view taken on line 5—5 of Fig. 3.

Referring now to the drawings in detail, the car is shown as of the rotary dump type with

35 fixed ends but it is obvious that it is equally well adapted for end dumping by the mere provision of an end door and possibly braces at the open end. The inner or side sills are of angle form having a vertical web 2 projecting into the lading

40 zone and an inturned bottom flange 4. The ends of the sills overlap and are connected to the sides

45 of the cast end members which are substantially of channel form braced by the inclined portions 8. One end member is provided with a

combined spring buffer and draft gear A, while the other member is provided with a rigid draw

element B and wood cushioned bumper cap C.

Each end member is provided with projecting flanges 10 to which is riveted the end wall 12

50 having its ends extending inwardly at an angle for connection to the plate girder side walls 14. The girder side walls extend the full length of

55 the car between end walls and are formed with an inturned bottom flange 16 secured to the outwardly directed flange 18 of a bottom chord of angular formation. As shown more clearly in

Fig. 5, the bottom chord of the plate girder is Z shaped in cross section, though this, obviously, is merely by way of example. The in-

50 turned lower flange 20 of the chord forms a sup-

port for the floor, while the web 22 being disposed inwardly from the plane of the side wall forms, together with the top flange, an admirable location for the attachment of the car haul members 24 without changing the clearances of the car. The top portion of the side wall is directed inwardly and upwardly as at 26 then upwardly at 27 to terminate in a rolled portion 28, and to this upper portion of the wall is attached an angle having one leg 30 secured to the main plane of the side wall while leg 32 is directed inwardly to be secured as by welding, to the inner portion of the side wall. A top chord of triangular formation is thus formed which is exceptionally strong and provides a ledge to receive 15 the car dumper clamps, while the inclined sheet insures complete clearing of the car when turned upside down in the dumper. The upper end portions of the side walls have a portion of the top roll removed as at 33 in order that straps 34 secured to the end wall may be also secured to the upwardly extending flange of the side wall to tie the sides together and assist the corner connection angles 36.

A substantially rectangular frame is thus 25 formed to which is secured the floor plate 38 preferably supplied as a single sheet with openings 40 cut therein to receive the wheels W and openings 42 for the insertion of tools to permit the driving of rivets. The floor as shown is suspended from the inturned flanges 4 and 20 of the sills and girder wall bottom chord respectively and from the end members and also from the end wall by means of the connection angles 44. The floor may, if desired, be formed in more than 35 one piece but in any case will be attached to, and supported by, the various flanges referred to previously.

The wheel hoods and cross support members are shown as pressed in one piece with side 40 flanges 46, upstanding walls 48, top wall or cover portion 50 which connects the side walls, and wall 52, dome-shaped hood portion 54, and outer end flanges 56. The hood and cross support member is formed by first pressing the hood 45 proper in the sheet, then by subsequent die operations the edge portions are gathered in to be finally pressed in the desired form as shown. Outer bearing member 58 of general Z form has the upper flange 59 directed inwardly for attachment to the wheel hood and to form a bearing portion for the outer end of stub axle 60, the inner end of which is received in bearing member 62 secured to the inner wall of the hood and to the upstanding flange of the angle sill 55 by suitable means such as rivets. The inner bearing has an upstanding central portion 64 placed at an angle to the vertical to be secured to the hood and to the upwardly directed flange of the brace as will be described later. The 60

hood and cross support members preferably have the bearing brackets connected thereto and properly aligned prior to attachment to the car and their attachment to the car is accomplished by securing the flanges 46 to the car floor, the end wall and inner bearing bracket to the sill flanges, the outer end flanges to the girder side walls and the outer bearing bracket flange to the floor sheet. It will be seen that the combined hood and support member, together with the girder walls and floor sheet, forms a full box section of great strength extending between the outer bearing member and side wall. The load on the car floor will be transmitted to the axles and wheels by the inner sills and by the box section support members, which latter receive the load from the girder side walls.

Braces 70 of inverted U form have flanges 72 secured to the floor sheet and these braces extend between the inner sill members substantially in alignment with the axles. The brace ends are flared upwardly as at 74 and provided with end flanges 76 to receive rivets securing the brace to the sill and also with upwardly directed flange 78 which secures together the brace, wheel hood and central extension 64 of the inner bearing bracket.

The various parts and construction of the car have been described in detail but it is obvious that changes may be made such as forming the support member as a pan-shaped pressing to which would be welded the dome-shaped wheel hood proper, or the pressing could be made in two parts welded together and these changes as well as others are contemplated which fall within the scope of the appended claims.

What is claimed is:

1. In a mine or similar car, girder side walls, sill members, combined wheel hood and support means connecting said sill members and girder side walls, a floor supported by said means and by said side walls and sill members, inner bearing brackets secured to said sill members, outer bearing brackets secured to said support means in spaced relation to said sills and side walls, said support means being substantially of closed box-section between said outer bracket and side wall.

2. In a mine or similar car, the combination of plate girder side walls having top and bottom chords, sill members spaced from said walls, combined wheel hood and support units connecting said sill members and plate girder side walls, a floor supported by said units and by said plate girder side walls and sill members, said floor extending under the wheel hood units and having wheel receiving openings formed therein, inner bearing brackets connected to said sill members, outer bearing brackets secured within said support means intermediate the girder side wall and adjacent sill member, said outer bearing brackets being also directly connected to the floor, and wheel supported axles extending between said brackets.

3. A combined wheel hood and support unit for mine and similar cars comprising, a unitary metal pressing having, upstanding side walls, an inner end wall, and a cover portion connecting said walls, said cover portion having a part thereof located in a substantially horizontal plane and a part thereof pressed upwardly to form a wheel hood.

4. A combined wheel hood and support unit for mine and similar cars comprising, a unitary metal pressing having, upstanding side walls, laterally directed flanges at the lower edge of the side walls, end walls, and a cover portion connecting said walls, said cover portion having a part thereof located in a substantially horizontal plane and a part thereof pressed upwardly to form a wheel hood.

5. In a mine or similar car, the combination of side walls each having a top chord and a bottom chord of angular formation including a horizontal portion and a depending portion arranged inwardly with respect to the wall, sill members spaced from said walls, combined wheel hood and support units connecting said sills and side walls, a floor supported by said units and by said side walls and sill members, inner bearing brackets connected to said sill members, outer bearing brackets secured to said support units intermediate the side wall and the adjacent sill member, and wheel supported axles arranged in said brackets, said angle shaped bottom chords forming recesses for the reception of car haul stops.

6. In a mine or similar car, a side wall having top and bottom chords, the latter being substantially Z shaped in cross section with the flanges thereof horizontally arranged whereby to provide a recess for the reception of a car haul stop, a sill spaced from said wall, a combined wheel hood and support unit connecting said sill and side wall, a floor supported by said unit and by said side wall and sill member, an inner axle bearing secured to the sill, an outer axle bearing arranged within and secured to said support unit between the side wall and sill, and a wheel supported axle arranged in said bearing.

7. In a mine or similar car, girder side walls, sill members, combined wheel hood and support units connecting said sill members and girder side walls, a substantially single level floor supported by said units and by said side walls and sill members, said floor extending under the wheel hood units and having wheel receiving openings formed therein, inner bearing brackets secured to said sill members, outer bearing brackets secured within said support means in spaced relation to said sills and side walls, said outer bearing brackets being also directly connected to the floor, and wheel supported axles extending between said brackets.

8. In a mine or similar car, girder side walls, sill members, combined wheel hood and support units connecting said sill members and girder side walls, a floor supported by said units and by said side walls and sill members, said floor extending under the wheel hood units and having wheel receiving openings formed therein, inner bearing brackets secured to said sill members, outer bearing brackets arranged within and secured to said support means in spaced relation to said sills and side walls, said outer bearing brackets being secured to the floor, wheel supported stub axles extending between said brackets, and means connecting said sills and units and located substantially in alignment with said stub axles.
